No. 793,550.

PATENTED JUNE 27, 1905.

H. S. STORMER.
SAFETY APPLIANCE FOR ENGINES.
APPLICATION FILED NOV. 22, 1904.

UNITED STATES PATENT OFFICE.

HARRY S. STORMER, OF JOHNSTOWN, PENNSYLVANIA.

SAFETY APPLIANCE FOR ENGINES.

SPECIFICATION forming part of Letters Patent No. 793,550, dated June 27, 1905.

Application filed November 22, 1904. Serial No. 233,879.

To all whom it may concern:

Be it known that I, HARRY S. STORMER, a citizen of the United States, residing at Johnstown, in the county of Cambria and State of Pennsylvania, have invented new and useful Improvements in Safety Appliances for Engines, of which the following is a specification.

This invention relates to a safety appliance for engines.

10 I shall show and describe the device in order to indicate its many advantages in connection with a steam-engine; but of course I do not limit the invention to such particular use.

15 The device operates in conjunction with a governor, it being of such a character that should the belt connecting the governor with the engine-shaft break or jump from its pulleys the engine will be at once stopped. I am familiar with a number of safety devices for 20 doing the same thing which have been in use, but which have been discarded owing to their failure to operate as intended at critical times, and even under the most favorable conditions these prior devices operate, if at all, only when 25 the engine with which they are associated is running under an even or uniform load.

25 I provide a safety device which is simple in construction, which requires no attention from an engineer, and which in no wise interferes 30 with the normal operation of an engine, and which assures the operation of the latter under a variable load.

35 In the drawings accompanying and forming a part of this specification I illustrate a simple adaptation involving my invention which I will set forth at length in the following description; but I do not limit myself to the disclosure thus made, for certain variations may be adopted within the scope of my claims succeeding said description.

40 Referring to the drawings, Figure 1 is a sectional side elevation of a safety appliance or governor mechanism involving my invention and showing the same associated with an engine of the Corliss type. Fig. 2 is an enlarged sectional elevation of a casing or boxing in which certain of the operating parts of the appliance are housed. Fig. 3 is a detail view of a rocking member. Fig. 4 is a detail 45 view of the outer end of the swing- 50

ing arm hereinafter more particularly described. Fig. 5 is a front elevation of the same. Fig. 6 is an elevation of certain of the parts appearing in Fig. 1 and as looking from the right in said figure toward the left, the 55 parts being the casing 10, the rod 11, and governor mechanism above the same.

Like characters refer to like parts throughout the different views.

In Fig. 1 I have illustrated portions of an engine of the Corliss type, with which my device will satisfactorily operate, the cylinder shown in Fig. 1 having the usual inlet or supply and exhaust valves. Loosely carried by the stems of the supply-valves are the angle-levers 2, one arm of each of which carries a forked link, as 3, the shouldered branch of which coöperates with a block 4, rigidly fastened to the outer end of a crank 5. The cranks 5 are rigidly connected with the two 60 supply-valve stems. The other branch of each link coöperates with a trip device on a collar 6. The two collars are loose on the supply-valve stems. Said collars 6 are connected to the governor (denoted in a general 65 way by 8) by means of the governor-rods 7 and rocker 7^a. The connections between the governor, which is of the "fly-ball" type, and the engine-shaft need not be described in detail except to state that they involve a belt, as 70 9, and it is with this belt that my safety device coöperates, its function being, as hereinbefore stated, to cause through coöperating means the stoppage of the engine should the belt break or jump or be pulled from its pulley. Of the several valve parts I have deemed it necessary to show only one of the supply or inlet valves and its immediate coöperating parts in order to illustrate the mode of operation of the safety device. Upon the collars 75 9^a are knock-off blocks 6^a, only one of which, however, is shown, and which coact with the safety device and with the links 3. During the normal operation of the engine these knock-off blocks 6^a, which have a back-and-forth movement below the inner branches of 80 said links, do not strike said inner branches, but on one stroke approach near the same. Should a belt break, however, the collars 6 85 will be permitted to have an abnormal move- 90 95 100

ment through the release of the governor 8 and governor- rods 7, and on this abnormal movement the knock-off blocks strike the links 3 and disengage the same from the blocks 4, 5 thereby to permit the instant closing of the supply-valves and the stoppage of the engine.

Associated with the governor-post in any desirable way is a casing or boxing, as 10, which may be made by casting or in any 10 other desirable way. The top of the casing or boxing 10 has a perforation or hole to receive the lower portion of the rod 11. Said rod 11, which is vertically disposed, extends between its ends through a perforation in the collar 12, clamped or otherwise suitably attached to the post or standard of the governor 8 and constituting a convenient guide for said rod. The lower end of the rod 11 rests upon the detent 13, indicated as a slide, suitably guided for 15 horizontal movement within the casing or boxing 10. The upper end of the rod 11 is arranged in the path of the forwardly-extending arm of the rocker 7^a and is engaged by said forwardly-extending arm on the downward movement thereof, the arm on its upward movement passing free of the rod. The rod, therefore, limits the motion of the rocker and necessarily of the governor and insures the normal operation of the engine, during 20 which normal operation, as will be understood from the foregoing statements, the knock-off blocks 6^a approach, but do not strike the links 3. Should, however, the governor-belt 9, as will hereinafter appear, break, the detent 13 25 will be automatically moved away from the base of the rod 11, so that the latter can drop automatically and away from the forwardly-extending arm of the rocker 7^a, freeing said arm and necessarily the governor, so that the 30 balls thereof can drop, and, in the present instance, impart, through the intermediate parts, a thrust to the governor-rods 7, in order that the knock-off blocks 6^a may be given their abnormal movement, hereinbefore indicated, to 35 cause them to trip the links 3 and free the two supply-valves.

Supported by the casing or boxing 10 is a rocking member made up of a shaft 14, provided with a crank-arm 15 at its outer end, 40 and an arm 16, disposed at right angles to the said shaft. The inner face of the hub of the arm 16 has a notch to snugly receive a lug 17 on the adjacent end of the rock-shaft 14, the relation mentioned being maintained by a bolt 18, extending through registering bores in the shaft and hub of the arm 16, respectively. The outer side of the hub of said arm 16 is reduced to fit for rocking motion a perforation 45 in the inner wall of the boxing or casing 10, the outer wall of said boxing or casing having an aligned perforation to receive for rocking motion the shaft 14. The nut of the bolt is outside of the casing 10, and between the nut and the casing a washer is interposed. 50 The bolt, with its nut and washer therefor,

not only maintains the two parts of the rocking member in rigid relation, but also holds said rocking member, made up of the shaft 14, arm 16, and associated swinging parts, in working connection with the casing. The upper end of the arm 16 is forked, the fork being adapted to enter a slot formed depthwise in the outer end of the sliding detent 13 and to receive between its branches a pin, as 19, extending transversely of the slot and which 55 may be in the form of a rivet.

In the opposite inner faces of the casing 10 are formed channels curved in cross-section to agree with the curvature of a bore 20, formed in the web of the boxing or that part 80 thereof joining the sides, said bore and channels constituting a seat and guiding means for a coiled push-spring 21, which is compressed by the arm 16, as will hereinafter appear. 85

It will be remembered that the rock-shaft 14 has a crank-arm 15, disposed outside of the casing 10. To this crank-arm may be bolted or otherwise suitably connected an elongated rod 22, the rod and its projection, herein-after described, constituting, in effect, a part 90 of the rocking member, to which I have hereinbefore alluded. Suitably associated with the outer end of the rod 22 is a spindle or stub-shaft 23, upon which the roller or wheel 95 24 is adapted to turn, the roller being removably connected with the spindle by means of a screw or bolt 25, and between the head of said screw or bolt and the outer face of the roller a washer is interposed. The wheel or 100 roller 24 when the safety device is in operative position is adapted to engage or rest against one of the runs of the belt 9, the upper run in the present case, during which time the sliding detent 13 will be in its normal position or one to limit through the rod 11 the movement of the governor 8 and assure the normal operation of the engine. The arm 16 at this time will be wholly housed within the casing or boxing 10 and will compress the 105 spring 21, so that should the belt 9 break or jump from its pulleys such act will at once release the swinging member, including in its make-up the rod 22. When the said rod is released, it will move in such direction as to 110 swing the arm 16 in a direction to carry its upper end out of the casing, and the arm being operatively united with the sliding detent the latter will be moved in a direction to release the rod 11 in order to permit the rod, 115 and hence the governor-balls, to drop and effect the stoppage of the engine in the manner hereinbefore described. It will be evident that I do not wholly rely upon the weight of the wheel or roller 24 in order to cause 120 the operation of the sliding detent in a direction to release the rod 11, but that I augment the effect of the wheel by the power of the spring 21. This, however, is not essential, 125 for I might rely wholly upon the spring or 130

wholly upon the wheel, these being matters of detail.

The engine illustrated is of the horizontal type; but the appliance will work equally satisfactorily with engines of another type, for, as I have indicated, I do not limit the use of the device to connection with any particular kind of engine.

The roller or wheel 24 is not directly carried by the body of the arm or rod 22; but its spindle is carried by a block 26, fitted between the branches of a bifurcation carried upon the outer end of said rod or arm. Through registering perforations in the branches and blocks bolts or equivalent holding-pins 27 pass in order to hold the roller normally at right angles to the said arm or rod, during which time it can rest against the belt 9. Should an engineer desire to test the operativeness of the device at any time, this can readily be accomplished by swinging the roller from off or away from the belt, which can be brought about as follows: The inner bolt or pin 27 will be removed, so that the roller and its carrier or block can be swung laterally away from the belt—that is to say, the roller will be swung bodily from off the belt and around the outer bolt 27 as a pivot—and when this is done the rod 22 can be swung in a direction to cause the release by the detent of the governor-limiting rod 11. When the rod is released, it can of course drop down exactly as it would do automatically if everything is in proper order. After the test has been made the roller and its carrier will be returned to their original positions and the inner bolt 27 inserted in place.

The safety device is thoroughly effective in operation and simple in construction. It does not prevent the normal or proper operation of the engine; but should the governor-belt break or be pulled from its pulleys the engine will be at once stopped.

The working parts of the safety appliance are housed, and in practice they will, as far as possible, be protected from the action of dust and flying particles.

The spring 21 not only assists the wheel 24 in shifting the rod 22 to bring about the action of the detent 13 in order to automatically release the rod 11 when the belt 9 breaks or jumps from its pulleys; but it also during the normal action of the parts holds the roller 24 against the belt in order to maintain the same in a tight condition.

Having thus described my invention, what I claim, and desire to secure by Letters Patent, is—

1. In an appliance of the class described, a normally stationary governor-limiting rod, a 60 slideable detent adapted to be engaged by said rod, and a swinging governor-belt-controlled member directly connected with said detent, said member being automatically shiftable on the breakage of the governor-belt and serving, 65 during such shifting motion, to operate the

detent in a direction to release said governor-limiting rod and permit shifting movement of the latter.

2. In an appliance of the class described, a sliding detent for controlling the movement of a governor, and a swinging belt-controlled member having a bifurcated arm, the said detent having a slot to receive the bifurcated portion of the arm and having a pin in the slot to fit between the branches of the bifurcation. 75

3. In an appliance of the class described, a sliding detent for controlling the movement of a governor, a rock-shaft provided with two arms, one of which is directly connected with the detent, a rod connected with the other arm and provided with a roller or wheel to engage a governor-belt, said wheel being mounted for movement into and out of engagement with the belt independently of said rod, and a spring arranged to act against that arm 85 which is directly connected with the detent.

4. In an appliance of the class described, a casing, a sliding detent in the casing for controlling the movement of a governor, said detent having a slot, and a pin in the slot, a rock-shaft supported by the casing, an arm connected with the rock-shaft in the casing, having a forked end fitted in said slot and arranged to receive said pin, and a rod connected with the shaft outside the casing and provided with a roller to engage a governor-belt. 95

5. In an appliance of the class described, a casing having a perforation to receive a governor-limiting rod, a sliding detent in the casing adapted to be normally engaged by the rod, and having a slot and a pin in the slot, an arm in the casing, having a forked end to enter the slot and to receive said pin, a rock-shaft extending into the casing and provided at its inner end with a lug, one side of the hub of said arm being notched to receive said lug and the other side of the hub being supported for rocking motion by that wall of the casing opposite that carrying the shaft, a bolt extending through the shaft and hub respectively, said shaft having on its outer side an arm, and a rod united to said last-mentioned arm and provided with a belt-engaging roller. 105 110

6. In an appliance of the class described, a sliding detent for controlling the movement of a governor, a swinging governor-belt-controlled member for actuating the detent and provided with a projecting portion movable into and out of engagement with the governor-belt independently of the said governor-belt-controlled member. 115 120

7. In an appliance of the class described, a detent for controlling the movement of a governor, a swinging governor-belt-controlled member for actuating the detent and provided with a roller arranged for movement into and out of engagement with the belt independently of the said governor-belt-controlled member. 125

8. In an appliance of the class described, a sliding detent for controlling the movement 130

of a governor, a swinging arm coöperative with, and provided with means for actuating, the detent, said arm being forked, a block fitted between the branches of the fork of the arm and carrying a roller to travel in contact with the governor-belt, and pins passing through the branches of the fork and the block, one of the pins being removable, whereby the block and the roller can be moved rel-

atively to the arm, to carry the roller out of engagement with the belt.

In testimony whereof I have hereunto set my hand in presence of two subscribing witnesses.

HARRY S. STORMER.
